UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF DELAWARE.

SHEET-COLLECTING MECHANISM.

1,267,354.

Specification of Letters Patent. Patented May 28, 1918.

Application filed October 3, 1917. Serial No. 194,517.

To all whom it may concern:

Be it known that I, HOWARD M. BARBER, a citizen of the United States, and resident of Stonington, in the county of New London and State of Connecticut, have invented a new and useful Improvement in Sheet-Collecting Mechanism, of which the following is a specification.

In sheet collecting mechanism it is very difficult to hold the sheets in register on the collecting cylinder as the collecting cylinder grippers open to collect the sheets and open to transfer the collection of sheets. This is especially true where a number of sheets are collected and transferred and where the sheets are heavy. The object of my invention is to provide means for insuring the proper holding of the sheets on the cylinder against slipping out of register while being collected and transferred, said means including coöperating end and side grippers for engaging the sheets, the side grippers closing on the sheets at the times that the end grippers open both to collect and to transfer the collection, the side grippers opening beyond the sides of the sheets as they pass the sheet collecting and collection transfer point so as not to interfere with the passage of the sheets.

30 In the accompanying drawings,

Figure 1 is a horizontal section through a portion of a sheet collecting mechanism illustrating my invention applied thereto,

Fig. 2 is a section taken in the plane of the line II—II of Fig. 1.

Fig. 3 is a detail view of one of the side grippers and its support.

Fig. 4 is a vertical section taken in the plane of the line IV—IV of Fig. 1, and

40 Fig. 5 is a vertical section taken in the plane of the line V—V of Fig. 1.

One or more webs pass over the web feed roll 1, through the pair of coacting sheet cutters 2, 3, and guides 4, 5, to the sheet collecting cylinder 6. This cylinder may have

45 one or more sets of end grippers 7 and one or more corresponding sets of side grippers 8. In the present instance, I have shown three sets of end grippers and three sets of side grippers; the side grippers being located a considerable distance back of the end grippers so as to engage the sheets at a point about midway their length.

50 The cylinder 9 may be a folding cylinder and its set of end grippers 10 is arranged

to take each collection of sheets from the end grippers 7 at the proper time. Each set of end grippers 7 is held normally closed by the spring 11; is opened to collect the sheets cut from the web or webs by a stationary cam 12; and is opened to transfer the collection to the cylinder 9, by a movable cam 13 brought into the path of the end gripper stud or roller 14 every one and one-third revolutions of the collecting cylinder 6, by a cam 15 carried by the cylinder 9.

The relative size of the cylinders 6 and 9 is such that a collection of sheets is transferred every one revolution of the cylinder 9 and every one and one-third revolutions of the cylinder 6.

The side grippers 8 of each set are pivoted at opposite ends of the cylinder 6, on brackets 15, the gripping fingers of the grippers swinging through slots 16 in the cylinder into and out of their sheet engaging position. The grippers are held normally closed by springs 17 and are opened by a stationary cam 18, which engages the gripper studs or rollers 19. The position and length of the cam are such that the side grippers are closed by their spring tension when the end grippers are opened by their cam 12 for collecting the sheets cut from the web or webs and also when the end grippers are opened for transferring the collection of sheets to the cylinder 9, thus maintaining absolute control of the sheets at all times on the collecting cylinder and preventing them from slipping out of register.

55 The cam 18 serves to swing the side gripper fingers out beyond the sides of the sheets as the grippers pass the sheet collecting and transfer point to permit the side grippers to freely pass.

It is evident that one or more webs may be passed through the cutters and the sheets or groups of sheets collected and transferred.

60 While I have disclosed my invention as applied to a three-way collecting cylinder arranged to collect four sheets or groups of sheets, it is obvious that I do not wish to limit myself to this particular arrangement, but

What I claim is:

1. Sheet collecting mechanism including a collecting cylinder having end and side grippers coöperating to collect the sheets thereon.

110

2. Sheet collecting mechanism including a collecting cylinder having end and side grippers coöperating to collect the sheets thereon, and to transfer the collection. 60
- 5 3. Sheet collecting mechanism including a collecting cylinder having end and side grippers, the side grippers serving to close on and hold the collected sheets as the end grippers are opened to receive additional sheets. 65
- 10 4. Sheet collecting mechanism including a collecting cylinder having end and side grippers, the side grippers serving to close on and hold the collected sheets as the end grippers are opened to receive additional sheets, and also as the end grippers are opened to transfer the collection. 70
- 15 5. Web sheet cutters, and a collecting cylinder having end grippers arranged to collect sheets fed from the cutters, and side grippers arranged to hold the sheets on the cylinder as the end grippers are opened to collect. 75
- 20 6. Web sheet cutters, and a collecting cylinder having end grippers arranged to collect sheets fed from the cutters, and side grippers arranged to hold the sheets on the cylinder as the end grippers are opened to collect and also as the end grippers are opened to transfer the collection. 80
- 25 7. Web sheet cutters, a folding cylinder, and a collecting cylinder having end grippers arranged to collect the sheets fed from the cutters and transfer the collection to the 85
- 30 35 folding cylinder and side grippers arranged to hold the sheets on the collecting cylinder as the end grippers are opened to collect. 90
- 35 8. Web sheet cutters, a folding cylinder, and a collecting cylinder having end grippers arranged to collect the sheets fed from the cutters and transfer the collection to the 95
- 40 45 folding cylinder and side grippers arranged to hold the sheets on the collecting cylinder as the end grippers are opened to collect and also as the end grippers are opened to transfer the collection to the folding cylinder. 100
- 45 9. Sheet collecting mechanism including a collecting cylinder having coöperating end and side grippers arranged to alternately engage and hold successive sheets of a collection on the cylinder. 105
- 50 10. Web sheet cutters, and a collecting cylinder having coöperating end and side grippers arranged to alternately engage and hold successive sheets of a collection on the cylinder. 110
- 55 11. Web sheet cutters, and a folding cylinder, a collecting cylinder having coöperating end and side grippers arranged to
- alternately engage and hold successive sheets of a collection on the cylinder, the side grippers serving to hold the collection as the end grippers are opened to transfer the collection to the folding cylinder. 115
12. Sheet collecting mechanism including a collecting cylinder having coöperating end and side grippers arranged to alternately engage and hold successive sheets of a collection on the cylinder, and gripper controlling means causing the side grippers to close as the end grippers open and vice versa. 120
13. Sheet collecting mechanism including a collecting cylinder having a sheet collecting point, means for feeding the sheets to said collecting point, and end and side grippers on the cylinder coöperating to collect the sheets thereon, the side grippers being arranged to hold the sheets on the collecting cylinder as the end grippers are opened at the sheet collecting point. 125
14. Sheet collecting mechanism including a sheet collecting cylinder having a sheet collecting and collection transfer point, means for feeding the sheets to said collecting point, and end and side grippers on the cylinder coöperating to collect the sheets thereon and to transfer the collection, the side grippers being arranged to hold the sheets on the collecting cylinder as the end grippers are opened at the sheet collecting and collection transfer point. 130
15. Sheet collecting mechanism including a sheet collecting cylinder having a sheet collecting point, means for cutting sheets from a web or webs and for feeding the sheets to said collecting point, and end and side grippers on the cylinder co-acting to collect the sheets thereon, the side grippers being arranged to hold the sheets on the collecting cylinder as the end grippers are opened at the sheet collecting point. 135
16. Sheet collecting mechanism including a sheet collecting cylinder having a sheet collecting and collection transfer point, means for cutting sheets from a web or webs and for feeding the sheets to said collecting point, and end and side grippers on the cylinder coöperating to collect the sheets thereon and to transfer the collection, the side grippers being arranged to hold the sheets on the collecting cylinder as the end grippers are opened at the sheet collecting and collection transfer point. 140

In testimony, that I claim the foregoing as my invention I have signed my name this 1st day of October, 1917.

HOWARD M. BARBER.
